HYDRAULIC TAPPET

Charles E. Johnson, North Muskegon, Mich.

Application October 5, 1936, Serial No. 104,086

12 Claims. (CL. 123—90)

This invention relates to self adjusting valve tappets to be used in connection with the valves of internal combustion engines, and more particularly of the hydraulic type disclosed in my copending applications, such as Ser. No. 625,622 filed June 29, 1932, or Ser. No. 585,859, filed Jan. 11, 1932.

In internal combustion engines the valve tappets are members which are given a reciprocatory movement in one direction from rotating cams fixed to or integral with a cam shaft. The valves for opening and closing an intake or exhaust port in the engine have stems which bear against the ends of the valve tappets, the valves being lifted when the cams move the tappets in one direction. Springs associated one with each valve move the valves in the opposite direction to close the valves when free to do so. These springs have relatively strong force and are compressed when the valve tappets lift the valves off their seats.

In valve structures of this kind a clearance between the tappet and its associated valve stem is required and this clearance has almost universally heretofore been the subject of very careful mechanical adjustment. The clearance between the tappets and the valve stems must be provided in such a manner that when the engine is hot the valves will not be lifted above their seats due to expansion of the parts when heated; therefore when the engine is cold there is a gap or clearance of a few thousandths of an inch between the tappets and the bearing ends of the valve stems which engage against the tappets. Furthermore, the clearance should not be any greater than is necessary as excessive clearance causes hammering of the valves on their seats, undue noise in operation and a disruption of a proper timing of the valves in their movement. In the present invention a hydraulic actuated adjustment of the tappet is provided which automatically takes up all clearance between the tappets and the valve stems and further automatically compensates for changes in the parts due to expansion or contraction with changes of temperature.

In hydraulic tappets of the character shown in my prior filed applications and also in the other usual designs of hydraulic tappets, unless the parts are very closely fitted, this being very costly in manufacturing, if the oil which is under pressure of the oil pump of the engine becomes thin or attenuated, as is quite likely when the engine is fully heated, the seepage or passage of oil which controls the engagement of the tappet

against the end of the valve stem between the tappet body and the guide sleeve in which it is mounted for reciprocation may be at such an amount when the engine is turning over at very low speed, that is, when the engine is idling, that the best operation of the automatic self adjusting tappet will not occur.

One of the objects of the present invention is to provide a very simple and practical means for controlling and preventing too rapid a passage or seepage of such oil whereby the tappet will function perfectly even though the oil is of a thin character and the engine at idling speed, and without the necessity of very close tolerances in manufacture of the parts.

Another object of the invention is to provide a tappet structure which is of a simple and very practical construction for large quantity production and with the greatest of economy in manufacture, so that cost may be kept at a minimum and to provide a tappet of readily manufactured and very easily assembled parts. These and various other objects and purposes will be understood from the following description taken in connection with the accompanying drawings, in which

Fig. 1 is a fragmentary section and elevation showing a usual valve arrangement in an internal combustion engine with a tappet embodying the present invention installed therein.

Fig. 2 is an enlarged longitudinal vertical section through the tappet with the part in one position.

Fig. 3 is a similar view showing the parts in another position and with the interior spaces of the tappet shown as filled with oil.

Figs. 4 and 5 are horizontal sections on the planes of lines 4—4 and 5—5 of Fig. 2 looking in a downward direction.

Fig. 6 is a perspective view of an oil sealing member used with my invention.

Fig. 7 is a view similar to Fig. 2 showing a slightly modified form of structure attaining the same purposes and results.

Fig. 8 is a horizontal section on the plane of line 8—8 of Fig. 7.

Fig. 9 is a longitudinal vertical section similar to Figs. 2 and 7 of a further form of structure for attaining the same results in the same manner.

Figs. 10 and 11 are horizontal sections respectively taken on the planes of lines 10—10 and 11—11 of Fig. 9 looking downwardly.

Fig. 12 is a section similar to Fig. 9 of an additional equivalent valve tappet structure and,

Figs. 13 and 14 are horizontal sections taken respectively on the planes of lines 13—13 and 14—14.

Like reference characters refer to like parts in the different figures of the drawings.

In Fig. 1 the wall of a cylinder is indicated at 1, a port, which may be an exhaust or intake port at 2 having a valve seat 3 at one end against which a valve 4 engages. The valve has an elongated stem 5 guided through a suitable sleeve-like guide 6. A heavy coiled compression spring 7 seats at one end against a seat member 8 on the valve stem and at the other end engages against a part of the engine block around the stem guide 6, the spring acting to draw the valve 4 into tight engagement with the seat 3 when free to do so. This is a conventional valve structure in internal combustion engines, there being at least one intake and one exhaust port for each cylinder of the engine and a valve associated with each of said ports.

In my invention the tappet includes a cylindrical substantially hollow body 9 closed at its lower end which has a mounting for vertical reciprocatory movements in a tappet guide sleeve 10. The tappet body 9 between its ends has a shallow and relatively wide groove 11 made continuously around it. Oil is pumped by the oil pump of the engine into a conduit 12 which is made along the bank of tappet guide sleeves 10, the oil being pumped thereinto through a lead-in pipe 13. It is evident that oil is pumped into the annular chamber at the groove 11 between the tappet body and the guide sleeve 10 is filled with oil under pressure. A cam shaft 14, which is continuously rotated when the engine is in operation, carries a plurality of cams 15, one under the lower end of each tappet, so that when the cam 15 passes underneath the body 9 of the tappet the valve 4 is lifted, compressing the spring 7, and after the cam has passed from the tappet the spring 7 returns the valve to its lower closing position.

As shown in Figs. 2 and 3, the body 9 has cast integral therewith an inwardly extending annular ledge 16, against which a member or plug 17 is pressed at the upper side, the part 17 having a press fit within the body of the tappet. A horizontal passage 18 is drilled through the member 17 aligning with the openings 19 made opposite each other in the walls of the body 9. In practice the passage 18 and the openings 19 may be drilled at the same time after the member 17 has been pressed into place. In the upper side of the body 17 a centrally located chamber 20 is made, a central vertical passage 21 surrounded by an upwardly extending lip 22 leading from the passage 18 to the chamber 20. A metal plate valve 23 having projecting ears 24 (Fig. 5) is located 60 within the chamber 20 and is adapted to rest upon the annular lip 22, the diameter of the body of the valve member 23 being substantially equal to the exterior diameter of the annular lip 22. A flat plate 25 rests upon the member 17 and 65 covers the chamber 20. At its central portion the plate 25 has a number of small openings 26 and, preferably at its center, it is pressed downwardly to make a projection 27 which serves as a stop against excessive upward movement or fluttering 70 of the valve 23.

Immediately above the member 17 and the plate 25 the body 9 is machined out to a slightly larger diameter, this being so that the member 17 and the plate 25 may be readily installed without forcing the same the entire length from the upper

end of the body 9. Within the upper portion of the body a piston 28 is mounted, having a portion 29 of reduced diameter at its lower part. The piston is of a hollow construction integrally closed at its lower end and having its upper end closed by a cap 30 preferably welded in place. The cap is of a conical form as shown in Figs. 2 and 3, though it need not necessarily be of such form, and has a head 31 at its upper end which comes directly underneath the lower end of the valve 10 stem 5.

In the form of structure shown in Figs. 2 and 3 the piston, at the shoulder between its larger portion 28 and smaller portion 29, is machined so as to have a downwardly and inwardly inclined face as shown at 32. A ring 33, parted at one side as shown in Fig. 6, bears at its outer curved surface against the inner walls of the body 9 and at its upper end has an inclined structure so as to fit snugly against the inclined shoulder 32. The inner diameter of the ring 33 is larger than the exterior diameter of the smaller part 29 of the piston thereby providing a continuous annular space or chamber 34 between the inner side of the ring 33 and the outside of the piston part 29. A coiled compression spring 35 bears at its lower inner end upon the plate 25 and at its upper end against the lower end of the ring 33 thereby pushing the ring upwardly until its inclined upper edge engages the inclined shoulder 32, whereupon the continuing force of the spring 35 tends to spread the ring 33 at its parting so that at its outer curved surface snugly engages the inner walls of the tappet body 9, in addition to the pressure of oil in chamber 34 which also presses the ring outwardly.

A continuous groove 36 is made around the ring 33 adjacent its upper end, and horizontal passages 37 are made from the groove 36 inwardly to the inner curved side of the ring 33, thereby communicating with the annular space or chamber 34. The body 9 has openings 38 positioned so that when the piston is in its lowermost position, shown in Fig. 2, the groove 36 comes into conjunction therewith. This eliminates any air that 45 may gather in the tappet. At the upper end of the body 9 an annular groove is made around the inner walls of the body and a parted spring wire snap ring 39 located in said groove preventing the piston from being withdrawn from the body 9 50 until the ring 39 has been removed.

In Fig. 7 the shoulder 32a shown is a horizontal shoulder instead of inclined, and the upper end of the ring 33a is made to correspond. The closure, having the head 31a at the upper end of the piston, is of a slightly different though equivalent form. The chamber 20 is the same but the valve 40 in said chamber is of a different construction being a circular plate with a plurality of small openings 41 in the peripheral portions thereof beyond the edges of the passage 21a leading from the chamber to the passage 18 in the member 17. The plate 25, instead of having a plurality of small openings 26 therein at its central portion, has a small central opening 26a of larger diameter.

In Fig. 9 the member 42, which occupies the same position and is the equivalent of the member 17, has an L-shaped passage 43 at its outer end in conjunction with an opening 19a in one side only of the body 9. The upper end of the L-shaped passage 43 communicates with a chamber 44 in which there is a ball valve 45 which, under gravity, closes the upper end of the passage 43. The chamber 44 is surrounded by a cylindrical

wall 46 which is made by cutting an annular recess in the upper side of said member. The chamber 44 is closed at its upper end by a pressed-in plug 47 which has small outlet openings there-5 through.

The piston 48 is of a modified structure being made of one part only and having a central vertical stem 49 which comes directly underneath the lower end of the valve stem 5. A spring ring 10 50 is seated in a groove made at the inner side of the piston 48 and has an end 51 bent to pass through an opening made in the wall of the piston 48, and enters an annular groove 52 in the inner wall and near the upper end 15 of the body 9. A split ring 53 of triangular cross section has an inner downwardly and inwardly inclined annular surface 54 shaped to conform to a complementary surface at the lower part of the piston 48. A coiled compression 20 spring 55 bears at its upper end against the ring 53 and enters the annular recess made in the member 42 around the cylindrical wall 46. The ring 53 has a continuous groove 56 around it, to serve the same purpose as the groove 36 in the 25 ring 33, and a plurality of passages 57 lead from the lower side of ring 53 upwardly and outwardly to the groove 56, for the escape of any air that may collect.

In the form of structure shown in Fig. 12 the 30 chamber 44, in which the valve 45 is located centrally of the member 42, is the same as in Fig. 9. The member 42 is similar to member 42 shown in Fig. 9, and 42 is covered by circular plate 58 which has a number of small openings 58a in its 35 central portion over chamber 44. The ring 53 is identical in structure with the ring 53 shown in Fig. 9 and a coiled compression spring 55a is located between the lower side of the ring 53 and the plate 58.

40 The piston 59 is similar to the piston 48 at the structure of its lower part. It has however a projection 60 at its lower end below the surface against which the inclined inner side 54 of ring 53 bears, around which the upper part of the 45 spring 55a is located. The open upper end of the piston 59 is closed by an inverted cup-like cap 61 which extends into and is permanently connected with the piston 59. The lower end of the valve stem 5 bears upon the upper side of the cap 61. A split spring ring 62 is seated in a groove around the outer curved side of the body 9 and at one end is bent inwardly at 63, passing through the wall of the body 9 and entering a groove 64 made between the upper end of piston 55 59 and the annular flange shown on the cap 61.

In the operation, as soon as the engine starts, oil is pumped through the pipe 13 into and around the body 9 and thence into the passage 18 filling the same and lifting the valve 23 in the 60 construction shown in Figs. 2 and 3, or the valve 40 in the construction shown in Fig. 7 or valve 45 in Figs. 9 and 12, thence passing upwardly to engage against and lift the piston of whichever form is used until engagement of the upper end 65 of the piston is made against the lower part of the valve stem 5. All clearance between the lower end of the valve stem and the upper end or head of the piston against which the lower end of the valve stem engages is taken up in a very 70 short time after the engine has started. As the parts expand due to rising temperature, the force of the valve spring 7, exerted through the valve stem against the piston mounted within the tappet body 9, causes a small amount of oil to seep 75 past the ring 33, and through its parting and

then between the upper enlarged end portion of the piston 28 in Figs. 2, 3, and 7, 48 in Fig. 9 or 59 in Fig. 12 so that the expansion is compensated for so that the valve 4 is not held above its seat.

When the engine is operating at low speeds or 5 is idling and the oil has become thinned or attenuated due to heating, without the ring 33, 33a, or 53 the seepage of oil past the upper enlarged part of the piston, when the valve is lifted on upward movement of the valve tappet, may become too great, so that at the lowermost position 10 of the valve tappet the lower end of the valve stem separates from the upper end of the piston and causes the tappet to become inoperative or operate incorrectly. The parted ring used checks 15 such seepage sufficiently that engagement of the lower end of the valve stem 5 with the head of the piston with which it is associated remains practically constant, and there does not occur hammering of the valve 4 on its seat and clicking or 20 other undesirable noises when the succeeding upward movement of the tappet strikes the piston therein against the lower end of the valve stem.

The rings used indicated at 33, 33a, and 53 are 25 of a size so as to be received readily within the tappet body 9. With structure shown in Figs. 2 and 3 there is a double force acting to expand the ring. One is the pressure of the oil in the annular space 34 against the inner side of the ring and the other the force of the spring 35 30 pushing the ring upwardly so that a wedging action is produced tending to expand the ring when its upper end engages the inclined shoulder. 32. In Fig. 7 a single hydraulic force tends to expand the ring at the proper cycle when the 35 valve 5 is lifted. This is the pressure of oil in the annular space between the lower part 29 of the piston and the inner curved side of the ring. In the structures shown in Figs. 9 and 12 there is not the same kind of oil pressure force tending to 40 expand the ring, but there is a wedging action due to the pressure of the spring 55 or 55a acting against the under side of the ring and bringing its inclined side 54 against the complementarily inclined surface on the piston 48 or 59. 45

It is quite common for air to become mixed with the oil and this will separate out and move to the highest level possible, that is, into the 50 annular chamber 34. The air is readily compressible and when the valve is raised the force of the valve spring 7 pushes the piston down to the position shown in Fig. 2 wherein an outlet for the air from the upper part of the chamber 34 is made through the passages 37 and the conjunction of the groove 36 with the outlet openings 38. 55 In Figs. 9 and 12, the air collected at the upper part of the space above the member 42 or plate 58 escapes through the passages 57 when the groove 56 in the ring is moved downwardly to the outlet openings 38a. 60

It will be evident that the machining operations of building the tappet in accordance with the disclosures made are of a kind conducive to high quantity production with low costs of manufacture. The body 9 may be finished by suitable 65 drilling or reaming operations to receive the member 17 or 42. Above this portion of the body the reaming of the same to size may be quickly accomplished. The members 17 and 42, also the pistons used may be machined rapidly on a lathe, 70 screw machine or other suitable mechanism. The holes to be drilled may be rapidly drilled and the production of the split rings used is also a high quantity production process. The valves are either simple stampings or balls, the plates 75

25 and 58 are likewise simple stampings. With this structure of tappet with machines rigged for the purpose the parts may be produced very economically and at high speed. The assembly 5 is also of the simplest character. After pressing the member 17 or 42 into place the other parts are put in in succession by mere insertion.

The constructions described are therefore not only particularly efficient to take care of the 10 problem of automatically adjusting the tappets to all conditions of engine operation, but the tappet structure itself may be cheaply manufactured and assembled. The claims appended here-to define the invention which is to be considered 15 comprehensive of all forms of structure coming within their scope.

I claim:

1. A valve tappet of the class described comprising, a hollow cylindrical tappet body closed 20 at its lower end, a plug having a press fit within said body member between the ends thereof, said plug and body member having lateral inlet passages for oil and said plug having a vertical outlet for said passage at its upper side and substantially at its center, a piston reciprocably mounted 25 within the body member above said plug, a valve at the inner end of said piston within the body member above the plug, said piston having a lower portion of reduced diameter with a shoulder 30 between the same and the upper portion of the piston, and a split ring having its upper edge bearing against said shoulder around the lower reduced portion of the piston and having its outer curved side bearing against the inner walls of 35 the hollow body member.

2. A construction containing the elements in combination defined in claim 1, said split ring having an inner diameter greater than the exterior diameter of the lower reduced portion of the 40 piston whereby there is provided a continuous annular space between the lower part of the piston and said ring.

3. A construction containing the elements in combination defined in claim 1, said shoulder between the larger upper and lower smaller parts of the piston having a downward and inward inclination to a horizontal plane, and the upper edge of said ring having a corresponding inclination, and a coiled compression spring between the 45 lower end of the ring and said plug.

4. A construction containing the elements in combination defined in claim 1, the interior diameter of said ring being greater than the exterior diameter of the lower smaller end of the piston 55 whereby a continuous annular space is provided between the ring and the adjacent sides of the piston, said ring having a groove around its other side and passages extending from said groove through the ring, and said body having a lateral 60 passage through the wall thereof in a position whereby the groove in the ring joins therewith in a lower position of said piston and ring for the purpose of expelling air.

5. A valve tappet of the class described comprising, a hollow body member of elongated cylindrical form having a closed lower end, a piston mounted for reciprocatory movements in the upper portion of said tappet body, valve carrying means within the tappet body below the piston 65 having an oil inlet passage and a valve associated therewith for controlling the passage of oil into the tappet body below the piston and stopping its passage in a reverse direction, an elastic ring surrounding the piston and bearing 70 at its outer curved side against the inner walls 75

of the tappet body, and spring means acting on the ring tending to outwardly expand the ring.

6. A construction containing the elements in combination defined in claim 5, combined with means providing a chamber for the collection of air in the oil between the piston and ring, and means providing for the escape of said air when the piston is moved downwardly in the tappet body to a predetermined position.

7. A valve tappet of the class described comprising, a tappet body member of elongated cylindrical form having an axial opening closed at its lower end, a plug secured in said body member between the ends thereof, said plug and body member having an inlet passage for oil and said body member having a valve chamber to which said passage leads, a valve within said valve chamber normally closing the passage, a piston in the body located above the plug, said piston having a lower end portion of a diameter less than the upper portion with an annular shoulder between the two parts of the piston, a packing ring around the lower part of the piston having its upper end bearing against said shoulder, the inner diameter of the ring being greater than the exterior diameter of the lower part of the piston whereby pressure of oil between the piston and the inner side of the ring tends to outwardly expand the ring.

8. A construction containing the elements in combination defined in claim 7, combined with a plate covering the valve chamber and having passages therethrough for oil, and a coiled compression spring having its lower end bearing against the upper side of said plate and its upper end bearing against the lower end of said ring.

9. A valve tappet comprising an elongated cylindrical hollow tappet body closed at its lower end, a plug having a press fit within the tappet body between its ends, said plug having a centrally disposed valve chamber and an oil inlet passage leading thereto at the lower end of the valve chamber, the opposite end of said passage having conjunction with an oil entrance opening through a side of the tappet body, a valve located within said valve chamber for closing said passage, a plate covering the valve chamber, said plate having an opening for oil passage, a piston mounted for longitudinal movements within the tappet body, said piston having a lower end portion of reduced diameter, a split ring within the tappet body around the lower part of the piston and bearing at its upper end against the lower end of the larger upper portion of the piston, and a compression spring between the lower end of 50 said ring and said plate.

10. A construction containing the elements in combination defined in claim 9, said ring having an inner diameter greater than the exterior diameter of the lower smaller part of the piston, thereby providing an annular chamber into which oil may enter and at the upper part of which air separating from the oil may collect.

11. A construction containing the elements in combination defined in claim 9, said ring having an inner diameter greater than the exterior diameter of the lower part of the piston, thereby providing an annular chamber into which oil may enter and at the upper part of which air separated from the oil may collect, combined with air escape means through said ring and valve tappet body, said ring and valve tappet body having passages leading from said chamber to the outside when the piston and ring occupy a predetermined position within the tappet body.

12. A valve tappet of the class described comprising, a tappet body of elongated cylindrical form, said body being hollow and closed at its lower end, a plug having a press fit into and located within the body between its ends, said plug in the upper central portion thereof having a valve chamber and a passage leading from said valve chamber laterally to a side of the body, and said body having an opening in conjunction with 5 said passage, a plate covering the valve chamber, a valve within the valve chamber below said plate, a piston mounted for reciprocating movements within the upper part of the body, said piston having a head at its upper end against

which the lower end of a valve stem is adapted to engage, said piston comprising an upper portion having an exterior diameter slightly less than the interior diameter of the upper part of the valve body and having a lower portion of a reduced 5 diameter with an annular shoulder between the upper and lower parts of the piston, and a split ring located within the tappet body having its upper end bearing against said shoulder and with its outer curved side bearing against the inner 10 walls of the tappet body, combined with means normally tending to cause the split ring to outwardly expand.

CHARLES E. JOHNSON.
